(57) **CLAIM**

The ornamental design for a trough basin, as shown and described.

DESCRIPTION

FIG. 1 is a front perspective view of a trough basin showing my new design;

FIG. 2 is a front elevational view of the trough basin seen in FIG. 1;

FIG. 3 is a rear elevational view of the trough basin seen in FIG. 1;

FIG. 4 is a right side elevational view of the trough basin seen in FIG. 1;

FIG. 5 is a left side elevational view of the trough basin seen in FIG. 1;

FIG. 6 is a top plan view of the trough basin seen in FIG. 1;

FIG. 7 is a bottom plan view of the trough basin seen in FIG. 1;

FIG. 8 is a front perspective view of another trough basin showing my new design;

FIG. 9 is a front elevational view of the trough basin seen in FIG. 8;

FIG. 10 is a rear elevational view of the trough basin seen in FIG. 8;

FIG. 11 is a right side elevational view of the trough basin seen in FIG. 8;

FIG. 12. is a left side elevational view of the trough basin seen in FIG. 8;

FIG. 13 is a top plan view of the trough basin seen in FIG. 8; and,

FIG. 14 is a bottom plan view of the trough basin seen in FIG. 8.

In the drawings, the broken lines depict portions of the trough basin that form no part of the claimed design.
